UNITED STATES PATENT OFFICE.

MOSES SAAD, OF DETROIT, MICHIGAN, ASSIGNOR OF FORTY-THREE PER CENT TO GUSTANDY OTALLAH AND FIVE PER CENT TO WALTER S. OSTRANDER, BOTH OF DETROIT, MICHIGAN.

MOLDING MACHINE.

Application filed October 2, 1925. Serial No. 59,985.

To all whom it may concern:

Be it known that I, MOSES SAAD, a subject of the King of Great Britain, residing at Detroit, in the county of Wayne and State of Michigan, have invented a new and useful Molding Machine, of which the following is a specification.

It is an object of this invention to provide a molding machine for production work wherein at least one match plate having a pattern secured thereon and one platten are so mounted on a constantly moving rotary machine that at a predetermined position of the machine the match plate is raised against the underside of a molding box, the platten is moved downwards to pack sand into the box and is then raised again after which the match plate is lowered from the molding box so that the latter may be taken away by suitable means while the machine continues to rotate.

Another object of the invention is to provide a molding machine having automatic means for permitting sand to flow into the molding boxes after the pattern has been raised into position in the box and prior to the lowering of the platten.

A further object of the invention is to provide a molding machine wherein the maximum and minimum heights of the racks on which the match plates and plattens are mounted are subject to adjustment.

With these and other objects in view which will be mentioned as the specification proceeds, the invention consists in certain novel construction and combination of parts hereinafter more fully described with the aid of the accompanying drawings, in which:

Figure 1 illustrates a plan view of the molding machine showing also part of the conveying mechanism that may be employed for carrying the molding boxes.

Figure 2 is a sectional elevation of the machine and also shows part of the conveying mechanism.

Figure 3 is an elevation of the machine showing the sand pipe and automatic means for operating the valve in the pipe.

Figure 4 is a section on the line 4—4 of Figure 2.

Figure 5 is a section on the line 5—5 of Figure 2.

Figure 6 is a detail illustrating the method of operating the valve in the sand pipe.

Referring to the drawings, 1 designates the bed of the machine to which an upright 2 is secured as by the nut 3. A sleeve 4 rotatably arranged around the lower part 5 of the upright rests on a ball thrust ring 6. Fast on the sleeve and in proximity to the thrust ring is a gear 7 which meshes with the pinion 8 on the shaft 9 which latter is driven by the motor 10.

Integral with the sleeve is a disc 11, and 11 indicates radial walls extending outwardly from the sleeve and upwardly from the disc. The number of these radial walls depends upon the number of molding units with which the machine is to be provided. Each radial wall has a guide 12 to carry a pattern rack 14 and a platten rack 15; 16 is a supplementary guide for the lower portion of the pattern rack. On each radial wall there are two segmental gears 17 and 18, one of which coacts with its pattern rack and the other with its platten rack.

On the upper end of the upright 2 two stationary plates 19 and 20 are secured as by cotter pins 21 and 22 respectively. In the plate 19 is a cam slot 23 and the plate 20 has a second cam slot 24. On the radial walls arms 25 are pivotally mounted the outer ends of which are adapted to travel round in the cam slot 23, and intermediately on each arm a connecting member 26 is fastened, the other end of which is connected to a segmental gear 17. A second set of arms 27 are also pivotally mounted on the radial walls and have outer ends which travel round in the cam slot 24. A connecting member 28 is fastened intermediately to each arm and also to one of the segmental gears 18. 45 and 46 are reinforcing plates placed against the sides of the radial walls.

At the lower end of each pattern rack 14 a match plate 29 is secured. A pattern 30 is fastened onto each match plate. The size of the patterns is preferably such that they will occupy most of the length and width of the molding box 31 and similarly the size of each platten 32 mounted on the lower end of its rack 15 is such as to nicely enter within the sides of the molding boxes.

From the arrangement of the cam slots 23 and 24 it will be noted that once during each revolution of the sleeve 4 the following movements will occur: The upper arms 25 are pulled inwards thereby raising the pattern racks 14 and the patterns 30 into position within the molding boxes, and the lower arms 27 are pushed outwards thereby lowering the platten racks 15 and plattens 32 10 against the sand 33 in the molding boxes. It will further be observed that the shape of the cam slots is such that the pattern racks will be raised in position prior to the lowering of the plattens, and that the latter will be raised again prior to the lowering of the pattern racks.

In the drawings the connecting members 26 and 28 are shown as turnbuckles with right and left hand threaded ends. The 20 object of this being to provide means for regulating the maximum and minimum heights of the racks without interfering with their length of travel, because from time to time molding boxes of different heights may be utilized. If it is desired to change the length or timing of the strokes of either or both the racks the stationary plates 19 and 20 are removed and replaced by others having differently shaped cam slots.

Obviously the movement of the molding boxes must synchronize with the movement of the disc 10, and moreover that portion of the conveyor travel which is in a circular path must correspond with the radius described by the machine. When the conveyor mechanism is similar to that shown in Figures 1 and 2 I employ peripheral notches 35 in the disc 10 to engage the conveyor members 36. When desired other means for carrying the molding boxes may be employed in which case it would probably be necessary to vary the engaging means between the machine itself and the conveyor.

Sand is conducted to the molding boxes through a pipe 37 having a valve 38. On the valve stem 39 is an arm 40 normally held in upward position by the counterweight 41, but as each radial wall comes into such position that one of the match plates 50 is in position under a molding box and the latter is under the sand pipe, one of the lugs 42 attached to the guides 12 contacts with the arm 40 and moves it partly round with the result that the sand valve 55 is opened and sand flows into the box underneath. As soon as the lug passes out of engagement from the arm 40 the valve is immediately closed by the counterweight 41, which pulls the arm 40 back against the stop 43.

In practice either mechanical or hand means are sometimes employed for tapping the sides of the molding boxes when the pattern rack makes its downward movement.

While in the foregoing the preferred em-

bodiment of the invention has been described as shown, it is understood that the construction is susceptible to such changes as fall within the scope of the appended claims. 70

What I claim is:

1. In a molding machine, a bed, an upright thereon, a sleeve around said upright, means for rotating said sleeve, guides on said sleeve, at least one pattern rack and one platten rack adapted to move vertically in said guides, and means for actuating said racks as said sleeve rotates. 75

2. In a molding machine as described in claim 1, the combination wherein the means for moving the pattern rack is independent of the means for moving the platten rack. 80

3. In a molding machine as described in claim 1, the combination wherein the means for moving the racks are so constructed that each rack makes one up and one down movement to each revolution of the sleeve. 85

4. In a molding machine, a bed, an upright thereon, a sleeve around said upright, means for rotating said sleeve, guides on said sleeve, at least one pattern rack and one platten rack in said guides, teeth on said racks, gears cooperating with said teeth, and means for turning said gears as said sleeve rotates. 90

5. In a molding machine, a bed, an upright thereon, a sleeve around said upright, means for rotating said sleeve, guides on said sleeve, at least one pattern rack and one platten rack in said guides, cam plates on said uprights having cam slots therein, and arms terminating in said cam slots which impart vertical movement to said racks as the sleeve rotates. 100

6. In a molding machine, a bed, an upright thereon, a sleeve around said upright, means for rotating said sleeve, guides on said sleeve, at least one pattern rack and one platten rack in said guides, teeth on said racks, gears cooperating with said teeth, cam plates on said upright having cam slots therein, arms terminating in said cam slots, and connecting members between said arms and said gears. 105

7. In a molding machine, a bed, an upright thereon, a sleeve around said upright, means for rotating said sleeve, guides on said sleeve, at least one pattern rack and one platten rack in said guides, teeth on said racks, gears cooperating with said teeth, a cam plate secured on said upright and having a cam slot therein by means of which said pattern racks are moved once up and down during each revolution of the sleeve, and a second cam plate also secured on said upright and having a cam slot therein by means of which said platten racks are moved once up and down during each revolution of the sleeve. 115

8. In a molding machine, a bed, an up-

right thereon, a sleeve around said upright, means for rotating said sleeve, a disc integral with said sleeve, radial walls integral with said sleeve, guides on each of said

5 radial walls, a platten rack and a pattern rack in each of said guides, and means for moving said racks vertically as said sleeve rotates.

9. In a molding machine, a bed, an upright mounted thereon, a sleeve around said upright, means for rotating said sleeve, a disc integral with said sleeve, radial walls integral with said sleeve and disc, guides on said radial walls, a pattern rack in a guide 15 on each radial wall, a platten rack in a guide on each radial wall, two stationary plates one above the other at the upper end of the upright each having a cam slot therein, and two arms mounted pivotally on 20 each radial wall, one of which extends into each cam slot.

10. In a molding machine, a bed, an upright thereon, a sleeve around said upright, means for rotating said sleeve, a disc integral with said sleeve, radial walls integral with said sleeve and disc, guides on said radial walls, a pattern rack in a guide on each radial wall, a platten rack in a guide on each radial wall, a segmental gear coacting with each of said racks and pivotally mounted on one of the radial walls, stationary plates secured towards the upper end of said upright, arms pivotally mounted on

said radial walls and extending into cam slots in said stationary plates, and a connecting member from each of said arms to one of said segmental gears.

11. In a molding machine, a bed, an upright thereon, a sleeve around said upright, means for rotating said sleeve, a disc integral with said sleeve, radial walls integral with said sleeve and said disc, stationary plates secured one above the other on said upright each having a cam slot therein, a guide on each of said radial walls, a pattern rack and a platten rack in each of said guides, teeth in said racks, a segmental gear meshing with each of said racks, all the segmental gears coacting with the pattern racks being actuated by arms terminating in one of the cam slots, all the segmental gears cooperating with the platten racks being actuated by arms terminating in the other cam slot, a platten at the lower end of the platten rack, and a match plate at the lower end of the pattern rack.

12. In a molding machine, a bed, an upright mounted thereon, a sleeve around said upright, means for rotating said sleeve, guides on said sleeve, pattern racks in said guides, and platten racks in said guides, in combination with lugs on said guides adapted to open a valve in a sand pipe as said guides rotate.

MOSES SAAD.
